DESIGN.

C. S. RAUBER
AIR PUMP CASING,
APPLICATION FILED OCT. 10, 1917.

51,532.

Patented Nov. 27, 1917.

FIG.1.

FIG.2.

INVENTOR:

Charles S. Rauber
By Davis & Simms
his attorney

UNITED STATES PATENT OFFICE.

CHARLES S. RAUBER, OF ROCHESTER, NEW YORK, ASSIGNOR TO HAUSER MACHINE & MANUFACTURING CO., INC., OF ROCHESTER, NEW YORK, A CORPORATION.

DESIGN FOR AN AIR-PUMP CASING.

51,532.

Specification for Design.

Patented Nov. 27, 1917.

Application filed October 10, 1917. Serial No. 195,864. Term of patent 7 years.

To all whom it may concern:

Be it known that I, CHARLES S. RAUBER, a citizen of the United States, residing at Rochester, in the county of Monroe and State of New York, have invented a new, original, and ornamental Design for an Air-Pump Casing, of which the following is a specification, reference being had to the accompanying drawing, forming part thereof.

Figure 1 is a perspective view of an air pump casing embodying my original design; and

Fig. 2 is a plan view of the new design.

I claim:

The ornamental design for an air pump casing, as shown.

CHARLES S. RAUBER.
